(57) CLAIM

The ornamental design for a game card holder, substantially as shown and described.

DESCRIPTION

FIG. 1 is a front perspective view of the game card holder, showing my design.

FIG. 2 is a front view thereof.

FIG. 3 is a back view thereof.

FIG. 4 is a left side view thereof.

FIG. 5 is a right-side view thereof.

FIG. 6 is a top view thereof.

FIG. 7 is a bottom view thereof; and,

FIG. 8 is a bottom perspective view thereof.

The broken lines in the drawings illustrate portions of the game card holder that form no part of the claimed design.

1 Claim, 6 Drawing Sheets
